UNITED STATES PATENT OFFICE.

MARY JANE REYNOLDS, OF ST. JOSEPH, MISSOURI.

RAILROAD SIGNAL AND GATE.

Application filed April 7, 1924. Serial No. 704,824.

To all whom it may concern:

Be it known that I, MARY JANE REYNOLDS, a citizen of the United States, residing at St. Joseph, in the county of Buchanan and State of Missouri, have invented certain new and useful Improvements in Railroad Signals and Gates, of which the following is a specification.

This invention appertains to railroad appliances, and the primary object of the invention is to provide a combined railroad gate and signal for railroad crossings, which will be automatically operated by a train approaching the said crossing.

Another prime object of the invention is the provision of novel means for constructing the gate, so that the same can be readily seen by persons approaching the railroad, whereby when the gate is in its operative position, the same will function as a signal or warning that a train is approaching.

A further object of the invention is to provide novel means for automatically operating the gate, said means including electrically operated throw levers, and novel means for closing the circuit to the electrically operated throw levers when a train approaches the crossing.

A still further object of the invention is to provide an improved railroad gate signal of the above character, which will be durable and efficient in use, one that will be simple and easy to manufacture and one which can be incorporated with a railroad crossing at small cost.

With these and other objects in view, the invention consists in the novel construction, arrangement and formation of parts, as will be hereinafter more specifically described, claimed and illustrated in the accompanying drawings, in which drawings:

Figure 1 is a plan view of a railroad crossing showing the combined gates and railroad signal incorporated therewith,

Figure 2 is a vertical section taken on the line 2—2 of Figure 1,

Figure 3 is an enlarged view similar to Figure 2 showing the gates in their operative position,

Figure 4 is a horizontal section taken on the line 4—4 of Figure 3 illustrating the levers for operating the gate,

Figure 5 is a diagrammatic view illustrating the circuits for controlling the combined gate and signal, and

Figure 6 is an enlarged section taken on the line 6—6 of Figure 5 illustrating the means of connecting the operating or throw levers together.

Referring to the drawings in detail, wherein similar reference characters designate corresponding parts throughout the several views, the letter A generally indicates a railroad track and B a road crossing, and C the novel combined gates and signals for the crossing. The track A is of the usual construction and includes the rails 10 and 11 and the supporting ties 12. In accordance with this invention the track A is divided into a block by insulating the tracks 10 and 11 as at 13 on each side of the crossing B.

The crossing B includes a chamber 15 formed under the tracks and this chamber is covered by a suitable top 16 formed of any desired material which forms the road-way. The chamber 15 can be formed of concrete or any other desired material.

The improved combined railroad gate and signal comprises a pair of companion portions or gates 17 and 18 arranged on each side of the roadway adjacent to the track A and each portion 17 and 18 includes a hollow post or casing 19 the top of which is provided with an annular guide flange structure. The casing 19 slidably supports a standard 21 the upper end of which has pivotally connected thereto as at 22 a plurality of plates or arms 23. These arms 23 are connected together at their terminals by flexible strips 24.

Now it can be seen that when a standard 21 is brought down into the casing that the arms 23 bearing against the annular guide flange 20 will be raised, so as to permit the lower ends of the arms to slide into the casing or hollow post. When the standard 21 is raised the arms 23 will automatically drop into an operative position as is clearly shown in Figure 3 of the drawings. The gate portions 17 and 18 are so arranged that when the gate portions are in their operative position as shown in Figure 3 of the drawings, the same will overlap one another so as to form a complete barrier across the roadway and thus prevent the driving of vehicles across the tracks. Owing to the shape of the gate portions the same also act as a visual signal for indicating to persons that a train is approaching the crossing.

The lower ends of the standards 21 have

pivots connected thereto, as at 25, the outer ends of the operating throw levers 26, which are pivotally secured at a point intermediate their ends as at 27 on suitable supporting brackets 28 which are arranged within the chamber 15. The inner ends of the throw levers 26 are pivotally connected together by suitable pivot pins 29 the terminals of which are mounted in guide ways 30 formed in a depending bracket 31 carried by the top 16 of the chamber 15. A relatively heavy expansion spring 32' is provided for engaging the inner ends of the throw levers 26 and this spring 32' normally serves to hold the standards 21 in their lowered positions so as to hold the gates 17 and 18 normally raised.

In order to automatically operate the gate portions 17 and 18 when a train approaches the crossing I have provided solenoids 32 and 33 which have their cores operatively connected as at 34 to the operating or throw levers 26. It can be seen that when the solenoids 32 and 33 are energized that the outer ends of the levers 26 will be raised which will slide the standards 21 upwards allowing the arms 23 to unfold. Thus the gate is in its open position when the standards are raised, as clearly shown in Figure 3 of the drawings. As soon as the solenoids are de-energized the spring 32' will force the inner ends of the levers 26 upwards and thus pull down on the standards 21, which will move the arms 23 to their folded position.

In order to energize the solenoids 32 and 33 I provide track relays 35 and these relays are located adjacent to the ends of the block. As shown each track relay 35 is connected with the rails 10 and 11 by wires 36 and 37 and as shown the wire 37 has interposed therein a track battery 38. When a train drives into the block, it is obvious that the circuit through the relays 35 will be completed and thus energize the relays which will attract the switch levers 40 which form the armatures for the relay. When the switch levers 40 are attracted by the relays the same engage the switch points for completing the circuits to the solenoids 33. The solenoid circuits include feed wires 42 and 43 which lead to the solenoids. The wire 42 has interposed therein a suitable battery 44 while the wire 43 has interposed therein the switch lever 40 and contact points 41.

From the foregoing description, it can be seen that I have provided an improved automatically operated railway gate which will be moved to its operative position when the train approaches the crossing and which

will be moved to its inoperative position 60 when the train leaves the crossing.

Changes in detail may be made without departing from the spirit or the scope of this invention, but:

What I claim as new is:

1. In a combined railroad gate and signal, a pair of gate portions, each including a hollow post, a standard slidably mounted in the post, and a plurality of flexibly connected arms pivotally secured to the upper ends of 70 the standards.

2. In an automatically operated railroad gate and signal, a pair of gate portions adapted to be arranged on each side of a roadway and adjacent to the railway tracks, 75 each including a hollow post, an annular guide formed on the upper end of each post, a standard slidably mounted in each post, a plurality of arms pivotally secured to the upper end of each standard, means for flexibly connecting the outer terminals of the arms together, and means for raising and lowering the standards.

3. In a railroad gate, a pair of gate portions, each including a hollow post having 85 an annular guide formed on its upper end, a standard slidably mounted within the post arranged to extend through the annular guide, arms pivotally secured to the upper end of the standard arranged to engage said 90 annular guide when the standard is lowered, means for flexibly connecting the outer ends of the arms together, and means for synchronously operating the standards.

4. In an automatically operated gate for 95 railway crossings, a pair of companion gate portions, each including a hollow post having an annular guide flange formed on the upper end thereof, a standard slidably mounted within each post, a plurality of 100 arms pivoted to the upper ends of the standards arranged to engage the annular guides when the standards are lowered, means for flexibly connecting the arms together, a pair 105 of operating levers, means for pivotally securing the levers at a point intermediate their ends, means for pivotally connecting the other end of the levers together, means for pivotally connecting the outer ends of the levers to the standards, and means for 110 operating the levers.

In testimony whereof I affix my signature in presence of two witnesses.

MARY JANE REYNOLDS.
